UNITED STATES PATENT OFFICE.

CLAUDE M. DIBBLE, OF JOLIET, ILLINOIS, ASSIGNOR TO MOORE BROTHERS COMPANY, OF JOLIET, ILLINOIS, A CORPORATION OF ILLINOIS.

STOVE CONSTRUCTION.

Application filed October 13, 1926. Serial No. 141,262.

The invention relates in general to stoves and more particularly to heating stoves having integrally formed ash pit compartments wherein by the provision of the ash pit parts, the provision of a neat and simplified stove assembly, having a light ash pit door and cooperating parts, is accomplished.

In previous stove structures embodying integrally formed ash pit compartments, the advantage of which over ash pits formed of a plurality of separate parts resides chiefly in the reduction of oven parts which simplifies assembly, reduces costs and results in a cleaner oven in which ashes, dust, etc. is confined in the one piece ash pit, it has been the practice to provide a sloping front wall. This necessitates a horizontally hinged ash pit door, which reduces the size of the ash pan for a given door opening due to the necessity of providing adequate clearance beneath the overhanging door. A vertically hinged door allows the use of an ash pan of maximum depth unreduced by the necessity of clearing beneath a horizontally hinged door and for a given stove capacity predicates the provision of a smaller door opening, a consequently smaller and lighter door and smaller and lighter door hinges.

The principal object of the invention is the provision of an integral ash pit compartment having a vertical front wall and a door supported on vertical hinges to close an ash aperture formed in the front wall of the pit compartment.

Another important object of the invention is to provide an ash pit which will receive or house a deeper ash pan and which provides a greater air space for the circulation of air through the stove and about the combustion chamber.

Another important object of the invention is to provide a method for moulding an ash pit part for heating stoves having a vertically disposed front or door receiving opening without requiring special coring or moulding operations.

Numerous other objects and advantages of the invention will be apparent as it is better understood from the following description, which, taken in connection with the accompanying drawings, discloses a preferred embodiment thereof.

Referring to the drawings:

Fig. 1 is a perspective view of a heating stove embodying my invention and having

parts thereof broken away to show details of construction;

Fig. 2 is a front elevational view of a lower portion of the stove taken from the left, (Fig. 1) and having parts including 60 the ash door broken away to show details of construction;

Fig. 3 is a similar view taken from the right (Fig. 2) having parts broken away to show details of construction; 65

Fig. 4 is a section taken substantially on line 4-4 in Fig. 2; and

Fig. 5 is a sectional view of a moulding flask illustrating the method of moulding the ash pit part of the stove. 70

To illustrate my invention I have shown a heating stove of the incased or cabinet type having a cabinet or housing 11, parts 12 and 13 providing a combustion chamber, a part 14 formed to provide an ash pit and 75 a base 15 arranged on or supported from a floor or like surface through legs 16. The cabinet 11 may be any cabinet or enclosure in which the parts 12, 13 and 14 may be mounted and having an air space or circulation chamber 17 about these parts in which air may be heated for heating a room or like enclosure and having a vertical wall 18 which is preferably the front or the wall on which a fire door 19, and ash pit door 21 85 are supported. The parts 12 and 13 may be formed separate or of one piece and in any suitable manner or form that is adapted for burning fuel and is formed to communicate with the fire door 19 so that the 90 combustion or fire may be controlled and maintained. The base part 15 may be of any suitable form that will support the parts 12, 13 and 14, and is preferably provided with a plurality of openings 22 through 95 which air may circulate from the bottom of the stove or from beneath the stove through the chamber 17 for heating. The legs 16 may be formed on the base or separate therefrom and suitably secured thereto, as desired. The part 14 may be formed in any suitable manner for supporting the stove parts 12 and 13 on the base 15 and is preferably of a solid or one piece casting having a laterally extending flange 23 adapted for 100 attachment to the base 15 and to be secured thereto by means of screws 24 or the like. The part 14 may be formed to support suitable stove grates which may be arranged on shafts 25 that are or may be suitably con-

105

110

nected through a pair of gears 26 so that rotation of either will cause rotation of one or more of the others. The part 14 may also support the parts 12 and 13 through a suitable flange 27 and is also formed to provide an ash pit 28 into which the fuel ashes may be collected for disposal. An ash pan 29 which is preferably formed in accordance with the form of the ash pit is arranged in the ash pit for removing the ashes. It is an object of the invention to produce a stove having an ash pit part that is formed so that it will have a vertical front wall and so that a vertically disposed door may make contact with the ash pit in a substantially vertical plane, further the ash pan 29 may be of a maximum size and the openings 22 in the base may be of a maximum size. To accomplish these results the mould for the part 14 is moulded so that the pattern draught or the angle of the substantially vertical contacting surfaces of the pattern and mould will have a movement toward and from each other during the withdrawal of the pattern and the assembly of the mould parts, so that in effect the ordinary draught or the draught of the ordinary tilted front wall of such a part will be transferred to or added to the draught of an opposite wall, such as the back wall. An opening 32 is also preferably moulded in this wall to provide an ash pit opening or an opening through which the ash pan 29 may be inserted and withdrawn. This opening is cast in the part 14 and without cores or like devices by casting the under surface of the top of the opening by one part of the mould and the top surface of the lower part of the opening by another part of the mould and splitting the mould along a line drawn between a point located at the junction of the outer and under surfaces of the front wall adjacent the opening 32 and a point located at the junction of the upper and inner surfaces of the wall. The front or outer surface of the wall 31 is or may be machined or otherwise finished to provide a substantially level and flush face and the ash door 21 may be similarly ground to seat perfectly against this surface. A locking latch 33 is provided with a handle 34 and is adapted to engage the wall 31 for locking the door 21 in closed position. The base part 15 may be formed to provide a well 35 into which the ash pan 29 may be seated if desired. I have illustrated in Fig. 5 one form of mould in which the part 14 may be cast or moulded, as above mentioned. The mould includes a drag mould part 36, a cope mould 37 and an intermediate mould 38. The inner contour of the part 14 is preferably moulded on the drag part 36 and is outlined by a solid line 39 and the part 14. The outer contour or surface of the part 14 is or may be partly moulded in the mould 38

and partly in the cope 37, or the mould 38 and cope 37 may be formed as a unit and the entire external surface of the part 14 formed by such unit. Lines 41 and 42 are vertical lines extending downwardly from points on the inner surface of the part 14 and lines 43 and 44 represent lines of draw or draught. These lines must always be at an angle to the lines 41 and 42 for moulding articles such as the part 14. If the part 14 were moulded in the flask in a horizontal position it would be necessary to mould the door at an angle equal to the necessary angle of draught and the door frame, or the front wall of the part 14 would therefore not be vertical. In order to make this wall vertical the part 14 is moulded in a tilted position or substantially as shown (Fig. 5) and so that the wall on one side of the part 14 will rest at an angle to vertical which is at least equal to the required draw or draught, and the angle of the opposite wall is equal to or approximately twice that of the draught so that the required draw will be present when the article or part 14 is being moulded and so that when the part is removed from the mould it will have a substantially vertical front wall in which the ash pit opening 32 is formed. In the present instance (Fig. 5) the device is shown tilted slightly in excess of the draught required so that the upper surface of the opening is moulded by the part 36 and the lower surface of the opening 32 is formed by the frame 38 or a combined frame and cope. Any suitable dowels or pins 45 may be provided on the mould part for aligning the mould during and after the sand moulding operation. When the ash pit 28 or part 14 is formed in accordance with my invention the ash pan may be materially larger since the stove parts 12 and 13 are shifted to a position nearer the front wall of the housing and the ash pan may fit snugly in the pit. The openings 22 in the base part 15 may also be larger permitting a larger volume of air to pass into the circulation chamber 17, thus permitting a larger volume of air to circulate through the stove or circulation chamber and increasing the heating capacity of the stove. The front wall 31 of the part 14 being vertical permits the door 21 to be substantially flat or a substantially flat sheet having a short flange extending thereabout which may be finished to make unbroken contact with the face of the wall 31 for tightly closing the stove draught and since the door 21 may be made narrower than a similar door that is arranged to abut against a tilted ash pit face the dust shelf on the top of the door which is formed by the flange thereof is materially decreased in width and the stove will for this reason not become soiled as readily or hold layers of unsightly dust as in similar devices. The

part 14 is preferably formed substantially rectangular in horizontal cross section so that a rectangular ash pan will be embraced by the side and back walls each of which are 5 preferably provided with at least some draught so that they may be moulded without tilting, coring or otherwise arranging the mould, and an ash pit is provided having at least one vertical wall and a plurality 10 of walls arranged at an angle to the vertical wall.

It is thought that the invention and many 15 of its attendant advantages will be understood from the foregoing description, and it will be apparent that various changes may be made in the form, construction and arrangement of the parts without departing from the spirit and scope of the invention or sacrificing all of its material advantages, the form hereinbefore described being 20 merely a preferred embodiment thereof.

I claim:

1. A stove structure, comprising, a stove housing, means in said housing providing a 25 combustion chamber, means for supporting said parts in said housing, said means comprising a base part supported in the housing and arranged to provide an ash pit having a substantially vertical front wall 30 provided with an opening for the removal of an ash pan and a plurality of walls disposed at an angle with said vertical wall, and a door hinged to the front wall of said ash pit and swinging in a horizontal plane 35 to close said opening.

2. In a stove structure, the combination 40 of a stove housing, parts providing a combustion chamber within said housing, a part providing integral ash pit walls including a vertical front wall arranged beneath said combustion chamber and adapted to support the combustion chamber in said housing, and a door supported by said ash pit

parts and arranged to close an ash pit opening formed in said vertical wall, said 45 door being arranged to contact with the vertical ash pit wall around said opening.

3. In a stove, the combination of a housing and parts arranged within said housing providing a combustion chamber, and a part 50 arranged to provide ash pit walls and to support said combustion chamber, said part comprising a vertical wall provided with a door opening and walls tapering from vertical lines surrounding the ash pit, and a 55 vertically hinged door arranged to close said opening by engaging said vertical wall adjacent said opening.

4. In a stove structure, the combination of parts providing a combustion chamber, a 60 part arranged to support said combustion chamber and to provide ash pit walls said part having a plane vertical wall provided with an opening through which an ash pan 65 may be removed and a door arranged to lie in a vertical plane and to engage the front surface of said vertical wall adjacent said opening when closing said opening.

5. In a stove structure, the combination 70 of a housing, parts arranged within said housing providing a combustion chamber, a part arranged to support said combustion chamber and to provide ash pit walls, said part having a vertical wall provided with an opening through which an ash pan may 75 be removed, and a door arranged to swing in a horizontal plane when closing said opening, said door being arranged to engage said vertical wall in a vertical plane.

6. In a stove structure, the combination 80 of a housing, parts arranged within said housing providing a combustion chamber, ash pit walls having a vertical wall, said wall having an opening therein and a vertically hinged door for closing said opening.

CLAUDE M. DIBBLE.
